UNITED STATES PATENT OFFICE.

RAYMOND A. HEISING, OF MILLBURN, NEW JERSEY, ASSIGNOR TO WESTERN ELECTRIC COMPANY, INCORPORATED, OF NEW YORK, N. Y., A CORPORATION OF NEW YORK.

CARRIER-WAVE SIGNALING SYSTEM.

Application filed December 1, 1924. Serial No. 753,029.

This invention relates to carrier wave signaling systems. A portion of the subject matter described herein is being claimed in applicant's copending application Serial No. 5 72,229, filed November 30, 1925.

An object of the invention is to insure a relatively constant frequency of the carrier wave used in carrier wave signaling systems.

10 A further object is to insure a relative constant frequency of the current derived from an oscillation generating system which includes the combination of an electric discharge oscillator feeding into a power amplifier.

These objects are achieved in one specific embodiment of the invention by using an oversize vacuum tube oscillator coupled with a power amplifier in the transmitting circuit, the oscillator being of the type in which the input and output circuits are capacitatively coupled. This expedient promotes a constancy of frequency of the oscillator by providing a relatively low 25 impedance shunt path for the potential variations occurring between the grid and filament, for example, of the power amplifier which would otherwise react on the oscillator to the detriment of its normal

30 function of generating a constant frequency. Since the operation of an oversize oscillator, as compared with that of a normal size oscillator is characterized by the generation of a larger amplitude of current in its output circuit, sufficient voltage for exciting the grid of the power amplifier can be obtained by using a larger condenser (hence a condenser of smaller impedance) for coupling the oscillator and the amplifier.

40 Other objects and features of the invention will be apparent from a consideration of the following detailed description taken in connection with the accompanying drawings, in which Figs. 1 and 2 illustrate the 45 circuits at the two respective terminal stations of a two-way radio communication system.

In the drawing the various elements of the system are labelled with identifying 50 symbols which are suggestive of the functions of the elements. For example, the letters W and E prefixed to the identifying

symbols respectively indicate that the elements are used at the west and east termini of the system. Similarly, the letters FB, 55 M, O, AS, AN, AP, SR, and D are used to indicate respectively, a band filter, a modulator, an oscillator, a speech amplifier, an antenna, a power amplifier, a speech scrambler, and a detector. The labels of elements 60 having similar functions at the two stations are differentiated only by the use of the letters W and E, and elements at the same terminus which have similar functions will be distinguished by the use of different subscripts. Graphical devices adjacent the circuits at various points depict, on a scale of abscissæ, the relative ranges occupied by the frequencies of the currents transmitted at 70 these points. Cross hatching between the vertical lines marking out these ranges identifies the portions of the frequency range occupied by signal currents. The vertical wave line hatching indicates the portion of the frequency range occupied by noise currents. It will be assumed that the circuits illustrated in Fig. 1 are at the west terminus and that the circuits illustrated in Fig. 2 are at the east terminus. 75

The system comprises a two-way radio 80 communication system for transmitting speech or other low frequency signals between a low frequency line 1 and radio apparatus adapted for two-way communication with a distant station including a similar arrangement of low frequency and radio apparatus constituting the terminal equipment of the east station of the system, to or from the east terminus which is similarly provided with transmitting and receiving 85 instruments. Although in Fig. 2 the transmitting and receiving instruments T and R are illustrated as unrelated, they may equally well be connected to a common low frequency line in a manner similar to line 90 1 at the west terminus. Transmission from west to east occurs through the circuits indicated in the upper halves of Figs. 1 and 2. Transmission from east to west correspondingly occurs by means of the circuits illustrated in the lower halves of these figures. 95 Although applicable to any point-to-point system the circuits are illustrated for use in a ship-to-shore radio communication system 100

for which it is especially well adapted the west terminus being the shore station and the east terminus the ship station.

At the west station, since the low frequency circuits used for transmitting and receiving are joined to a common low frequency transmission line, a means must be employed to insure substantial conjugacy of these circuits, so that low frequency transmitted waves will not enter the radio receiving circuits to impair their efficiency for simultaneous or future reception, and so that the received waves will not enter the radio transmitting circuits to set up a "singing" condition. The triple-wound transformer or hybrid coil 3 and artificial network N are provided for this purpose. The theory and application of hybrid coil arrangements in connection with balancing networks are now well known and do not appear to require further description in this specification.

The circuits for eastward transmission, intermediate the hybrid coil at the west station and the receiver R at the east station are illustrated in some detail. The corresponding circuits for transmission westward are indicated diagrammatically since the elements of this circuit are in large part duplicates of the corresponding elements of the eastward transmission circuit. The operation of the circuits for eastward transmission will now be considered in detail.

Voice currents from the low frequency line 1 pass through the hybrid coil 3, into low frequency line 2. These speech currents will be assumed, for convenience to comprise frequencies between the limits of 200 to 2500 cycles. These currents are divided, one portion flowing through branch circuit 4 and the other through branch circuit 5. The currents flowing in these respective circuits are distinguished by the different relative frequency ranges which they occupy. The frequencies of the currents flowing through circuit 4 occupy the ranges from 200 to 800 cycles and from 1500 to 2500 cycles. The currents flowing through branch 5 occupy the range from 800 to 1500 cycles. The necessary frequency segregation required to produce this result is accomplished, respectively, by the filter circuits WFB and WFB₁. These filter circuits are respectively designed to pass, without appreciable attenuation, the currents lying within the frequency limits to be transmitted respectively through circuits 4 and 5 and to suppress the currents lying outside these limits. Filters for this purpose may be designed in accordance with the disclosure in U. S. Patents 1,227,113 and 1,227,114, May 22, 1917, and 1,493,600, May 13, 1924, to Campbell.

The combination of elements included in branches 4 and 5 constitute what will hereinafter be called a "speech scrambler" and

that included in branch 5 a "speech transposer". The speech sub-bands transmitted through branch 4 are transmitted unchanged to circuit 6. The speech sub-band traversing branch 5 is transposed to a higher or lower level by combining it in modulator WM with oscillations supplied by the oscillator WOM. For practical purposes, it is convenient to transpose this sub-band to approximately a position in the frequency spectrum between 2700 and 3400 cycles. The reason for so choosing the frequency range to which the sub-band is transposed will be described later. For this purpose the frequency of the oscillator WO₁ should be 1900 cycles. The sum frequencies of the impressed currents is selected by band pass filter WFB₂. This will result in a transposition of the frequency band with no other change. If the frequency of the oscillator were made 4200 cycles and the difference frequency components, instead of the sum frequency components, were selected by band pass filter WFB₂, there would result a similar transposition and also a complete inversion of the frequencies in the band.

The step of transposing and inverting frequencies in accordance with the method just described is disclosed in U. S. Patent to Van der Bijl 1,502,889, issued July 29, 1924.

The transposed sub-band transmitted through branch 5 and the unchanged sub-band traversing branch 4 are supplied to circuit 6, where, accordingly, they occupy three distinct frequency ranges; one between 200 and 800 cycles, the second between 1500 and 2500 cycles and the third between 2700 and 3400 cycles. This represents greatly distorted speech. Obviously, the transposed sub-band could be made immediately adjacent the second sub-band, or it could be displaced further therefrom but still within the range of audible frequencies.

The unoccupied portion of the speech range, between frequencies 800 and 1500 cycles, is caused to be occupied with noise currents. These may be supplied to circuit 6 by a variable frequency oscillator WO. The element WO may be of any conventional type of oscillator circuit in which the frequency of the wave produced is determined by the natural frequency of an electrical circuit comprised therein. A Hartley type of oscillator circuit such as is described in U. S. Patent to Hartley 1,356,753, issued October 26, 1920, is illustrated. The frequency of the oscillations supplied by WO is made variable at an audible rate by including in the frequency determining circuit of the oscillator, a variable condenser driven by a motor 8. The addition of the noise currents to the "scrambled" speech currents results effectively in a further distortion of the speech currents. The resultant distorted speech currents are incapable of use in intel-

lignant communication, unless special means complementary to those just described, are used to restore these currents to their initial condition.

- 5 The distorted speech currents are transmitted through transformer 9 to vacuum tube speech amplifier WAS, which functions in the conventional manner. The amplified speech currents are impressed, through transformer 10, upon modulator WM₁, wherein they are combined with a high frequency carrier wave supplied by the vacuum tube oscillator WO₁. The resultant modulated wave is amplified in power amplifier WAP 10 and radiated from antenna AN.

The oscillator WO₁ is of the well known Colpitts type, which is disclosed in Canadian Patent No. 203,986, September 14, 1920. It is distinguished from other well known oscillator circuits by a capacitive coupling, constituted by condensers 11 and 12 in the oscillator of Fig. 1, between its output and input circuits. The frequency is determined by the natural frequency of the circuit comprising these condensers and inductance 15. The condensers 14 and 13 play no part in the operation of the oscillator, except to block the direct current supplied by the space current source 16, so as to confine 25 currents from this source to the space path within the tube. These condensers are accordingly made to have large capacity as compared with that of condensers 11 and 12. This oscillator is coupled to the power 30 amplifier by connecting together the filaments or cathodes and grids, respectively, of the two devices. The power amplifier can accordingly be considered as coupled to the oscillator through the series combination of 35 condensers 12 and 14.

The system of modulation employed is that commonly denominated "constant current modulation", one example of which is illustrated and described in U. S. patent to 45 Heising No. 1,442,147, January 16, 1923. The specific arrangement illustrated is a variation of that described in the above patent and is described in British Patent 168,056, August 31, 1922 to Heising. The plate 50 circuits of the modulator and the power amplifier are supplied with space current from a direct current source 16, through a low frequency choke coil 17. The modulator is in effect a variable impedance device the function of which is to cause a variable flow of 55 current through the space path of the power amplifier WAP in response to and in accordance with impressed signal frequency variations, and accordingly, because of the 60 resultant potential drop across the choke coil 17, to cause corresponding variations in the potential applied to the plate of the power amplifier. These low frequency variations in the plate potential of the power 65 amplifier are effective to cause correspond-

ing variations or modulations of the amplified carrier oscillations.

High frequency choke 18 prevents the high frequency currents supplied by the oscillator WO₁ from flowing through the low frequency circuits. 70

The particular modulating arrangement shown differs from that described in the above mentioned U. S. patent principally in that the low frequency variations are produced in the space potential of the power amplifier, instead of in the space potential of the oscillator. The arrangement is preferred in particular cases, where it is desirable to maintain constancy of oscillation 75 greater than can be secured by the means described in the U. S. patent in which the oscillator oscillates directly into the antenna. 80

A feature of the circuit is the means for deriving negative potentials for the grids of the speech amplifier WAS and the modulator WM₁. The direct current source 16¹, which supplies space potential to the modulator and power amplifier is used for this purpose. A resistance 19 is inserted between 90 the negative terminal of this source and the cathodes of the modulator and speech amplifier. The grids of the two devices being connected at the junction point with this arrangement the space current flowing through the resistance 19 produces a drop of potential across the resistance which is impressed upon the grids of the speech amplifier and modulator. This drop of potential will be 95 substantially constant since on account of the type of modulation used, the current is substantially constant. In order to further insure an absence of fluctuations in the current flowing through the resistance 19 due to the operation of the modulator, source 16¹ or other cause, a condenser 20 is connected in shunt to the resistance. This condenser is of low impedance for current of the frequency of these fluctuations, and hence provides a shunt path through which they are diverted about the resistance 19. The use of the resistance and shunting condenser in this relation accordingly insures that a 100 negative potential of constant value is impressed upon the grids of the amplifier and modulator, and thereby makes it unnecessary to use a separate source for this purpose. Obviously, this expedient may be employed to supply biasing potentials to any one or all of the discharge devices used in the system if 105 found desirable.

Another feature of the above described system resides in the use of an "over-size" oscillator WO₁. Its use results in a reduction of the reaction on the oscillator of the power amplifier on account of the shunting effect of certain of the amplifier tube impedances. An over-size oscillator is distinguished from a normal size oscillator by a 115 design which results in a greater amplitude 120

of current in its output circuit than would be required by its normal operation in the system. With the larger amplitude of current sufficient voltage for exciting the grid 5 of the power amplifier can be obtained by using a larger coupling capacity supplied by condensers 12 and 14, than would be necessary if a smaller size oscillator were used. The grid-filament and grid-plate resistance 10 and capacity of the power amplifier have a much smaller effect on the frequency of the oscillator because of the small reactance that would be paralleled. This results in a greater constancy of frequency in the oscillator, and, therefore, in the system as a whole. This expedient is of value, for example, where it is desired to simplify the transmitting circuits as by substituting a single stage for a multi-stage power amplifier. A simplification of this kind tends to 15 result in greater frequency variations in the system. Since simplification of this particular kind means a reduction in the power of the set the expedient is useful in securing 20 substantially as great a constancy of frequency in small power transmitting sets as can be achieved by other means in large power sets. Because of the economy of space and power there required this expedient is especially applicable on board ship as 25 in Fig. 2, in the system of which as well as in that of Fig. 1, this expedient may be used. In a typical instance the use of this expedient made possible the use of only four tubes 30 of only two sizes a four watt speech amplifier tube and two hundred and fifty watt modulator, oscillator and power amplifier tubes.

The modulated wave radiated from the 35 station of Fig. 1 is received by the antenna AN_2 of Fig. 2, which is tuned broadly to the carrier frequency. This wave is selected by a selective means FH , which may take the form of a high frequency band pass filter, or 40 a tuned circuit, and is detected in device ED . This device may be a vacuum tube or any other type of device capable of demodulating the received modulated wave.

The wave resulting from detection is identical with the distorted low frequency wave 45 supplied to the transformer 9 of Fig. 1. The "scrambled" speech currents of this wave to the exclusion of the noise currents are selected by filter circuits EFB_3 and EFB_4 . The former EFB_3 selects the sub-band lying 50 between 200 and 800 cycles and 1500 and 2500 cycles. The latter EFB_4 selects the sub-band between 2700 and 3400 cycles. These filters are similar in function to filters WFB and WFB_1 respectively of Fig. 1 55 and may be similar in construction.

The frequencies selected by filter EFB_3 are transmitted unchanged through circuit 60 21, to receiver R . Currents selected by filter EFB_4 are shifted back to the position in the

frequency spectrum that they initially occupied, that is, to 800 to 1500 cycles. This is accomplished by modulator EM_2 , oscillator EO_3 and band pass filter EFB_5 , according to a method analogous to that occurring 70 in branch circuit 5 of Fig. 1. The resultant sub-band is impressed on the receiver R . The superposed sub-bands impressed on this receiver, constitute a band which is identical with that supplied to the circuit 2 of 75 Fig. 1.

There has accordingly been provided, in the transmission channel above described, means whereby a casual or unauthorized operator can intercept and reproduce the 80 transmitted messages only with great difficulty, whereas the desired receiving station is equipped with special means insuring efficient reception of such signals. An interceptor in order to achieve any substantial degree of success in reading the signal messages would have to be equipped with unscrambling means substantially identical 85 with those above described.

The operation in transmission westward is 90 similar to the eastward transmission above described, except as affected by the fact that transmission is from ship to shore instead of from shore to ship. The elements EO , EFB , EAS , EM_1 , EO_1 and EAP function similarly to the elements WO , WFB , WAS , WM_1 , WO_1 and WAP of Fig. 1. The apparatus indicated by block EST is a speech transposing arrangement 95 similar to that included in branch 5 of Fig. 1. The modulated wave in the output circuit of the power amplifier EAP is impressed through transformer 22, an antenna AN_1 , which functions both as a transmitting and 100 a receiving antenna. The relation of the parts of the antenna circuit whereby it may operate efficiently for transmitting and receiving is described in Canadian Patent 232,492, July 3, 1923, to Heising.

The waves transmitted from antenna AN_2 110 of Fig. 2 are received by antenna AN_1 of Fig. 1. Since this figure illustrates a shore station, it is convenient to use separate antennæ for transmitting and receiving. By properly relating the antennæ geographically or geometrically interference and singing at that station can largely be avoided. Although a method of reception similar to that of Fig. 2 may be used at the shore station, the alternative method illustrated in 115 Fig. 1 can equally well be used and perhaps provides a more selective arrangement for distinguishing between desired and undesired incoming waves. The waves received by antenna AN_1 are combined, with oscillations supplied by a local source WO_2 , in high frequency detector or demodulator WDH . This detector functions as a frequency combining device to produce a wave 120 of intermediate frequency, equal to the fre- 125

130

quency difference between the received carrier wave and the oscillations from source W_0_2 , modulated by the distorted speech currents. The intermediate frequency modulated wave is selected by a circuit 23, which may be a tuned circuit as illustrated, or a band pass filter, and is amplified in the intermediate frequency amplifier WAI. The amplified waves are demodulated in the detector WDI and the resultant distorted speech currents are selected and amplified by device WAS₁. The rectangle WST represents a speech transposing arrangement which corresponds to EST of Fig. 2. WST comprises elements which cooperate in the same manner as the element EFB₄, EM₂, EO₃ and EFB₅ of Fig. 2. The band pass filter WFB₃ functions in a manner similar to filter EFB₃ of Fig. 2. The circuits comprising the two branches including devices WFB₃ and WST accordingly together constitute a speech unscrambling circuit. The reorganized speech wave resulting from the unscrambling operation are impressed 25 through hybrid coil 3 on low frequency line 1.

It will be obvious that the general principles herein disclosed may be embodied in many organizations widely different than those illustrated without departing from the spirit of the invention. Accordingly, it is to be understood that this invention is not limited to the arrangements or specific details disclosed but only by the scope of the appended claims.

What is claimed is:

1. A source of oscillations comprising an evacuated vessel containing a cathode, an anode and a third electrode, and an oscillation circuit having a capacitatively reactive path between said third electrode and said cathode and a separate capacitatively reactive path between said anode and said cathode; an electric discharge repeating device comprising at least two electrodes; means connecting said two electrodes to one of the pairs of electrodes of said source between which there is a capacitatively reactive path; said source being designed to produce an energy output greater than would be required for efficient amplification of said output by said repeating device.

2. The combination specified in claim 1 in which the power output of the source is substantially equal to the normal power output of the device. 55

3. In combination, an electric discharge repeating device comprising at least two electrodes, an electric discharge oscillation source, and capacitative coupling means between said source and said electrodes, said means also comprising a portion of the frequency determining circuit of said source, the capacitative reactance of said means being made small as compared with the impedance of said device between said electrodes, and said source being designed to produce a sufficiently large output current that the current flow in said means, with the value of the capacity reactance, provides an efficient 70 coupling between the source and device for distortionless repeating of the oscillations generated by said source. 65

4. In combination, an electric discharge repeating device comprising at least two electrodes, an electric discharge oscillation source, and capacitive coupling means between said source and said electrodes, the capacity reactance of said means being made small as compared with the impedance of said device between said electrodes, and said source being designed to produce sufficiently large output energy that the current flow in said means, with the value of the capacity reactance, provides the proper potential for 85 distortionless repeating of the oscillations generated by said source. 75

5. In combination, an electric discharge repeating device comprising at least two electrodes, an electric discharge oscillation source, and capacitive coupling means between said source and said electrodes, said means also comprising a portion of the frequency determining circuit of said source, said means taken in connection with the proportions of the various elements of the source being such that the source produces wattless energy which is large as compared with the wattless energy flowing between said two electrodes of the repeating device. 90 95 100

In witness whereof, I hereunto subscribe my name this 26th day of November, A. D., 1924.

RAYMOND A. HEISING.
